SYNCHRONIZING APPARATUS

Maurice Artzt, Haddonfield, N. J., assignor to
 Radio Corporation of America, a corporation of
 Delaware

Application July 26, 1938, Serial No. 221,299

7 Claims. (Cl. 178—69.5)

My invention relates in general to apparatus for maintaining two or more driven machines in synchronous relationship each to the other, and more particularly to such apparatus as applied to the idea of maintaining the operation of a facsimile recording machine synchronous with respect to the scanner.

Synchronizing arrangements per se have been known in the prior art, but they have suffered from various disadvantages. For instance, in one type of synchronous arrangements used, the prime mover or motor which operated the machine could very easily stop on dead center, that is to say, that the machine might assume such a position when stopped that synchronizing signals would not complete the driving motor energizing arrangement, and hence a severe disadvantage occurs.

Accordingly, it is one of the objects of this invention to provide an arrangement whereby the driving motor may be energized and maintained synchronously operating regardless of the relative positions of the apparatus when stopped.

Again, in at least one of the better known synchronizing arrangements, the driving motor is "jogged" at regular intervals unless a synchronizing signal is received which prevents such jogging. The phenomenon of fading may easily prevent the receipt of such a signal, and hence while the machine may be in exact synchronism, nevertheless, the motor will be jogged due to the fact that no synchronizing signal actually has been received to prevent this occurrence, and as a result the machine actually may be thrown out of synchronizing relationship with the scanner in the case of facsimile transmission. Accordingly, it is another of the objects of my invention to provide a device whereby synchronous relationship may be maintained even if some of the synchronizing signals are not received, provided the signals transmitted are of maximum amplitude for white.

Again, in the arrangement shown in the prior art, the synchronizing apparatus per se has been somewhat difficult to adjust, assemble and maintain correct adjustment. Accordingly, it is another of the objects of my invention to provide a synchronizing arrangement which is both simple, accurate, and easy to adjust.

Furthermore, it has been found that due to varying characteristics of motors in so far as slippage is concerned, one motor may slip a great deal more easily than another, this effect being caused by tight bearings or, in the case of a motor that has low slip, the bearings will be loose. Some way should be provided to take care of this varying

slipping function and, accordingly, it is another of the objects of my invention to provide an apparatus whereby the characteristics of any motor may be adequately compensated so as to provide a definite pole slipping function. In this respect, this invention comprises an improvement on the arrangement disclosed in the co-pending application entitled "Synchronizing apparatus," Serial No. 221,300, filed concurrently herewith by Mr. C. J. Young.

Similarly, a vacuum tube with age may change its characteristics, and also since probably no two vacuum tubes even of the same type have identical characteristics, some compensatory measures should be used in order to assure definite and adequate synchronizing influence. Accordingly, it is another of the objects of my invention to provide an arrangement in which this is done.

Therefore, the objects of my invention are:

1. To provide an arrangement whereby the driving motor in a facsimile recorder may be energized and maintained synchronously operating regardless of the relative positions of the apparatus when stopped.
2. To provide a device whereby synchronous relationship may be maintained even if some of the synchronizing signals are not received in a signal on white system.
3. To provide a synchronizing arrangement which is both simple, accurate, and easy to adjust.
4. To provide an arrangement for compensating for the varying pole slipping characteristics of any driving motor in a machine of this nature.
5. To provide an arrangement wherein the varying characteristic of a vacuum tube with age, or of different vacuum tubes of the same type when used in such a device, may be adequately and definitely compensated.

The operation in general is as follows: In the art of facsimile transmission, it is common practice to place an image to be transmitted onto a drum known as the scanner drum, and as this drum is rotated electrical impulses are developed sequentially which are representative of the optical values along each linear strip of the image. Since, necessarily, the reconstruction of the facsimile of the optical image must be made line by line, the material on which the image is to be recorded is usually passed around, or adjacent to, a recording drum which must operate synchronously with the movement of the scanner drum in order to reconstruct a true facsimile. One such type of recorder is shown in Reissue Patent #20,152 granted to C. J. Young on October 27, 1936.

In this patent, there is disclosed a recorder drum around which is provided a single turn helix. Adjacent the helix is positioned a presser bar, and between the presser bar and the helix there is passed a material on which the image may be recorded and a sheet of carbon paper, and the action of the presser bar is such as to leave a smudge of elementary area on the recording material where the bar strikes the helix. For more detailed information reference should be had to that patent.

The receiver for such a device is provided with two tubes, a so-called "black" tube and a so-called "white" tube. The "black" tube conducts when the said incoming signals are representative of black in the picture, and continues to conduct well up in to the white section of the picture. On the other hand, the "white" tube does not begin to conduct until currents representative of a medium value of white are impressed thereon, and the action of these two tubes taken conjointly is such as to give a desirable linear, or accentuated, operation in reconstructing the picture. This arrangement per se is not the entire subject-matter of this invention, and reference should be had to my co-pending application Serial No. 737,720, filed July 31, 1934, showing such an arrangement.

Now, in accordance with my invention, synchronizing impulses are transmitted in a "black" sense. There is joined to the recorder in an appropriate position, either directly connected to the scanning drum or otherwise, an insulating member having a commutating segment of substantially an L-shape. Adjacent the commutating segment there is provided three brushes which are not in contact with each other. The brushes are adapted to bear upon the insulating disc or member and to eventually, during the cycle of operation of the disc, come into contact with the commutating segment. These brushes are adjustable. Two of the brushes form a part of a relay energizing circuit, and the third brush has a function which will be hereinafter explained. The relay is connected in the output circuit of a tube which is biased so that it is responsive to picture signals and to the synchronizing signals. Thus when the commutating segment closes the gap between these two brushes, if the machine is in synchronism, a synchronizing signal should be received, and no current will flow in the aforementioned tube since the tube is driven to plate current cut off by the synchronizing signals which are transmitted in the black sense.

However, should the machine be out of synchronism, picture signals will be transmitted at the time the commutating segment closes the gap between the two brushes, and thus the relay will be energized. This relay then performs a dual function.

Adjacent the relay are a pair of contact members and a pair of armature members, the latter which may be interlocked. If the machine be out of synchronism and the relay is energized, one contact which is normally closed with one armature will be opened, and this contact and armature being in the driving motor circuit, it will cause a jogging of the motor.

Simultaneously, the second armature will be pulled down into contact with the second contact member, the latter being joined to the aforementioned third brush. This then places the energizing voltage for the plates of the white and black tubes substantially in parallel with the relay through appropriate resistance members, and

thus the relay is held in a locked position as long as the third brush is in contact with the commutating segment.

The third brush hereinbefore referred to is located at the lower and hence longer part of the L-shape segment and, therefore, the relay will remain closed or locked longer than the period during which the plate current alone of the "white" tube would keep the relay closed. As this brush is adjustable, the locking time and hence the time that the motor energizing circuit remains open is a function of the position of this brush with respect to the commutating segment and the other brushes. Hence, any variation in slippage in the motor may be compensated.

Again, the resistors through which the relay winding is energized being variable in nature, compensation for the variations in the characteristic of the vacuum tubes may be adequately compensated.

My invention will best be understood by reference to the drawing in which the single figure thereof shows one embodiment of my invention.

Referring to the figure, there are shown two vacuum tubes 1 and 2 having anode, cathode, control and screen electrodes. Tube 1 is appropriately biased so that it is conducting when signals are impressed on the control grid thereof which represent from lower black to medium grey or up into the light section of a transmitted picture. Tube 2 is appropriately biased and operated so that it does not respond to signals in the lower black region but begins to take hold, so-to-speak, when the signals representative, for instance, of grey are impressed on the control grid thereof and continues conducting up into the white section of the image. The operation of these tubes as shown provides an arrangement by which the presser bar, which has been hereinbefore referred to in connection with Reissue Patent #20,152 granted to C. J. Young, may have a substantially linear response, or the response may be accentuated as desired.

Connected in the anode circuit of tube 1, as shown in the drawing, is one of the coils 3 which is adapted to actuate the presser bar and which is identified in the drawing as the black printer coil. Similarly connected in the anode circuit of tube 2 is a further coil which is adapted to actuate the presser bar hereinbefore referred to and which is identified as the white printer coil. The screen grids in this instance are connected together and to the anode and a source of positive potential plus B is applied to the anode of each of the tubes through the connection between the screen grids and the circuit of the anodes. The negative side of this source of energy is grounded.

A potentiometer 5 is connected in parallel with the source of energy for the anodes of the tubes. The movable terminal 6 of this source of energy is connected through a relay winding 7 to one brush 8. A second brush 9 which is adjacent brush 8 is then connected to the anode of the white tube. Positioned immediately adjacent the core of the relay winding 7 is an armature 10 which may be mechanically coupled with a second armature 11 so that the action of the two is simultaneous. A contact 12 is normally held in engagement with the armature 10, and this arrangement forms a switch which is connected in series with the energizing circuit of the prime mover which is driving the apparatus.

Adjacent the armature 11 is a second contact member 13 which is normally held out of contact

with armature 11, that is parallel with armature 10 which is normally retracted with respect thereto. Connected in series with contact 13 and the armature 11 is a resistor 14 which is grounded at the extremity opposite this connection.

Also connected in series with the armature 11 and the contact 13 is a third brush 15 which is a compensating brush.

Positioned adjacent the three brushes and normally in wiping relationship with respect thereto is an insulating disc 16 which is driven in this case through a gear 17, a worm 18, and a driving motor 19.

Arranged on the face of the disc is an L-shaped commutating segment 20. Brushes 8, 9 and 15 are adjustable with respect to the commutating disc and to each other.

The operation of the device is as follows: During the interval that the synchronizing signal is sent, current will flow only in the "black" tube in view of the fact that the "white" tube does not conduct for currents representing a "black" value and, as has been hereinbefore stated, the synchronizing signal is transmitted in the "black" sense.

For synchronous operation of the machine, the conducting segment 20 comes into a position whereby brushes 8 and 9 are connected together by the segment at the interval that the synchronizing signal is transmitted. Since these brushes are connected through the relay energizing coil across the "white" printer coil, no current will flow through the relay coil 7 during the receipt of the synchronizing signal and, as a result, the armature 10 and the contactor 12 will remain closed and thus the energizing circuit for the driving motor is unaffected.

However, should the machine not be in synchronism, the segment 20 will not connect the brushes 8 and 9 at a time when the synchronizing signal arrives and, as a result, when the segment 20 does close the brushes, signals representative of a picture line are being received and hence have "white" components. This means then that the "white" tube will be conducting. Hence, the relay coil 7 will be energized sufficient to flutter the armatures 10 and 11, and the armatures 10 and 11 will be drawn toward the core of the relay which opens the motor circuit for a short interval of time. When the armature 11, which is normally retained in a retracted position with respect to contactor 13 comes into contact with the member 13, the resistor 14, brush 15, relay coil 7 and a portion of resistor 5 are connected in series. This means then that as long as the brush 15 is in conducting relationship with the segment 20, the relay coil 7 will be energized and the armatures will be locked in position. Since the lower part of the L-shaped segment 20 is longer than the section which contacts the brushes 8 and 9, the relay will remain locked for a period of time greater than that during which the two brushes 8 and 9 normally would hold the motor jogging arrangement open. Furthermore, since brush 15 is adjustable, the locking time may be definitely adjusted to fit any slippage conditions of any particular driving motor. In view of the fact that the locking system operates from the potential drop across a portion of resistor 5 as taken off by the potentiometer-moving contact 6, this potential may be so adjusted that changing characteristics of any tube, or different tubes, may be adequately compensated.

It should be understood that when I speak of the scanner and recorder operating in synchro-

nous relationship, what is meant is not only that the driving motors are running at equal speeds, but that the scanner drum and the recorder drum are being operated in phase.

It also should be understood that when I speak of transmission on "white," I mean that the signal amplitude increases as the scanned picture point gets lighter in shade. A signal on a "black" system naturally would be the reverse.

It will be appreciated that there may be a number of departures which are within the spirit and scope of my invention and, accordingly, I am not limited to the specific embodiment except as identified in the following claims.

What I claim is:

1. An apparatus for maintaining a facsimile scanner and at least one recorder in synchronous relationship each with the other and wherein synchronizing signals corresponding to picture black and indicative of the position of said scanner, and picture signal are transmitted comprising means for receiving said signals, a first thermionic amplifying means responsive in a range from black to at least within the grey portion of the picture, a second thermionic amplifying means responsive from a range of white to at least within the grey section of the picture but which is without the range of black, a motor, a source of energy for driving said motor, a commutator operable by said motor, the position of said commutator being such that it is at a predetermined position when said synchronizing signals are received when running synchronously with the scanner, means to interrupt the source of energy for said motor, means for actuating said interrupting means connected in the output circuit of one of said thermionic amplifiers, means for controlling said actuating means positioned adjacent said commutating segment, and means for locking said actuating means for a predetermined interval of time.

2. An apparatus for synchronizing a facsimile scanning device and at least one recorder and wherein electrical synchronizing impulses corresponding to black and indicative of the operating position of the scanner and picture impulses are transmitted comprising means for receiving said impulses, a first thermionic amplifier responsive to electrical impulses representative of black, a second thermionic amplifier biased normally to a non-conducting state during the receipt of black impulses and responsive to picture signals, means for impressing said picture and synchronizing signals onto the input circuit of said thermionic amplifiers, a driving motor for said recorder, a source of energy for said driving motor, a commutator operated by said driving motor and positioned so as to attain a definite position when said machines are operating synchronously, a pair of brush members positioned adjacent to and in contact with said commutator during a portion of its operating cycle, a series circuit including the anode of the second thermionic amplifier, a source of energy for said amplifiers, a relay coil and said brushes, means actuatable by said relay coil for interrupting the source of energy for said driving motor, and means for locking said relay for a predetermined period of time when said pair of brushes go from a conducting relationship to an insulating relationship with respect to said commutator.

3. An apparatus for synchronizing a facsimile scanning device and at least one recorder and wherein electrical synchronizing impulses corresponding to black and indicative of the operating

position of the scanner and picture impulses are transmitted comprising means for receiving said impulses, a first thermionic amplifier responsive to electrical impulses representative of black, a second thermionic amplifier biased normally to a non-conducting state during the receipt of black impulses and responsive to picture signals, means for impressing said picture and synchronizing signals onto the input circuit of said thermionic amplifiers, a driving motor for said recorder, a source of energy for said driving motor, a commutator operated by said driving motor and positioned so as to attain a definite position when said machines are operating synchronously, a pair of brush members positioned adjacent to said commutator and in contact therewith during a portion of its operating cycle, a series circuit including the anode of said second amplifier, a relay coil and said brushes, a pair of contact members positioned adjacent said relay coil, a pair of armature members positioned adjacent said relay coil and said contacts, the first of said armatures normally being held in a position touching one of said contacts and the second of said armatures being positioned so as to be normally retracted from contact with the second of said contacts, the first armature and contact member being connected in series in the motor energizing circuit, a third brush positioned adja-

cent said commutating segment and adapted to be in contact therewith during at least a part of the time that one of the pair of contact members is in contact with said segment, and means for joining said third brush member to the negative of the energy for said thermionic tubes.

5. Apparatus in accordance with claim 3 wherein said commutator is an L-shaped conductor and wherein a variable resistor is provided in 10 series with the relay coil.

6. Apparatus in accordance with claim 1, wherein said commutating segment comprises an L-shaped conducting member.

7. Apparatus in accordance with claim 1, 15 wherein said commutating segment comprises an L-shaped member, and wherein the means for controlling the actuating means positioned adjacent said commutating segment comprise a plurality of brush members for co-acting with said segment.

8. Apparatus in accordance with claim 1, 20 wherein said commutating segment comprises an L-shaped member, and wherein the means for controlling the actuating means positioned adjacent said commutating segment comprise a plurality of brush members for co-acting with said segment, and wherein the position of said brushes is adjustable with respect to said segment.

MAURICE ARTZT.
